UNITED STATES PATENT OFFICE.

HENRY C. SWAN, OF OSHKOSH, WISCONSIN.

KING-BOLT SOCKET.

SPECIFICATION forming part of Letters Patent No. 578,586, dated March 9, 1897.

Application filed July 25, 1896. Serial No. 600,481. (No model.)

To all whom it may concern:

Be it known that I, HENRY C. SWAN, a citizen of the United States, residing at Oshkosh, in the county of Winnebago and State of Wisconsin, have invented certain new and useful Improvements in King-Bolt Sockets; and I do hereby declare the following to be a full, clear, and exact description of the invention, such as will enable others skilled in the art to which it appertains to make and use the same.

The object of my invention is to provide a cheap, simple, and novel king-bolt socket and means for fastening it to the axle; and the invention consists in the construction and combination of parts hereinafter described and claimed.

In the drawings, Figure 1 is a plan view of my invention. Fig. 2 is a rear elevation thereof, and Fig. 3 is a sectional side elevation.

Referring to the parts by letters, A represents the front axle.

B represents a plate having a vertical part b , which is adapted to lie against either the front or rear face of the axle, and a curved top b' , which is shaped to conform with the top of the axle and extend a greater or less distance down on the opposite side of the axle.

30 This plate may be in part secured to the axle by the horizontal bolts b^2 , which pass

through the axle and the vertical portion b of the plate.

C represents a vertical king-bolt socket which is integral with the vertical part b of the plate and is centrally placed thereon.

D represents a clip having a bifurcated rear end, thereby forming two parallel legs d . The front end of the clip has a single leg d' . This clip embraces the plate B and the axle, the two legs d lying upon opposite sides of the king-bolt socket. These three legs d d' pass through the clip-yoke E, which lies against the bottom of the axle, and the nuts d^2 screw upon the ends of said legs.

Having described my invention, I claim—

The combination of a plate B having a vertical part and a curved top, and a vertical king-bolt socket which is formed centrally upon the vertical part of the plate B and is integral therewith, with the axle, a clip embracing said plate and axle, and having a single leg at one end and two legs at the other end which lie on opposite sides of the king-bolt socket, and the clip-yoke, substantially as and for the purpose specified.

In testimony whereof I affix my signature in presence of two witnesses.

HENRY C. SWAN.
